UNITED STATES PATENT OFFICE.

ALBERT E. COOK, OF ODEBOLT, IOWA.

ADJUSTABLE SIDE CURTAIN.

1,237,173.

Specification of Letters Patent. Patented Aug. 14, 1917.

Application filed February 27, 1911. Serial No. 611,169.

To all whom it may concern:

Be it known that I, ALBERT E. COOK, a citizen of the United States, and a resident of the city of Odebolt, in the county of Sac 5 and State of Iowa, have invented certain new and useful Improvements in Adjustable Side Curtains; and I do hereby declare that the following is a full, clear, and exact description of the same, reference being had 10 to the accompanying drawings, and to the numbers of reference marked thereon, which form a part of this specification.

Much inconvenience and delay is occasioned in putting on and taking off the side 15 curtains of automobiles equipped with cape tops, and this is true also of horse drawn vehicles and of launches and other boats equipped either with a cape top or a canopy top of any kind, whether adjustable or stationary, and with which side curtains are 20 used. This inconvenience arises in part from the fact that usually no convenient and quickly accessible place of carriage for the side curtains is provided on such vehicles or boats. In consequence, delay is occasioned in obtaining the side curtains for 25 use or in stowing the same after use, and, inasmuch as side curtains are usually constructed of a number of pieces, considerable 30 time is required in attaching the same to the car and in detaching the same from the car. This, in any event, occasions exasperating delay, and in many instances, delay in attaching the side curtains exposes the 35 occupants and the operator to the storm to an extent to occasion great discomfort or endanger health.

The object of this invention is to provide 40 in connection with either a collapsible top or a permanent stationary top of any kind, quickly adjustable curtains adapted to close the space beneath the top and applied to the sides or to the sides and ends, as preferred.

It is also an important object of the invention 45 to afford a receptacle for each curtain when not in use, into which the curtain is automatically retracted and in which it is yieldingly held until required for use.

It is also an object of the invention to afford 50 a construction in which the curtains may be quickly removed as a whole, if desired, by simply lifting the receptacle therefrom place.

The invention for convenience, is shown 55 embodied in connection with a cape top of an automobile, although adaptable for use

in connection with any kind of a top or canopy and for any sort of a device or vehicle.

The invention embraces many novel features and consists in the matters hereinafter described and more fully pointed out and defined in the appended claim.

In the drawings:

Figure 1 is a view in side elevation of 65 an automobile equipped with curtains embodying my invention.

Fig. 2 is a rear end elevation thereof.

Fig. 3 is a side elevation of the receptacle for the curtain, showing the same broken 70 away.

Fig. 4 is a broken section on line 4—4 of Fig. 3.

Fig. 5 is a fragmentary transverse section to illustrate the guides for the curtain, as 75 shown installed in Fig. 1.

Fig. 6 is a transverse section of the receptacle and curtain, showing the curtain retracted therein.

Fig. 7 is a fragmentary side view illustrating the means for engaging the free end 80 of the curtain in adjusted position.

Fig. 8 is a fragmentary detail of the engaging means shown in Fig. 7.

Figs. 9 and 10 illustrate respectively fragmentary front and side elevations of curtains applied to the wind shields.

As shown in the drawings:

1, indicates the vehicle or device to which the curtain is applied, in this instance (but 90 for convenience only) shown as an automobile. 2, indicates the top or canopy, in this instance (though not necessarily so) shown as the ordinary cape top of an automobile secured as usual to the body of the 95 automobile and projecting forwardly over the front wind shield 3. In the cape top construction shown, the rear brace bow 4, for the top, is connected in any suitable manner with the canvas or other covering 100 of the top, and also with the rear end walls or strips 5, which extend around the bend of the bow and downwardly and are secured around the back of the rear seat or to any corresponding portion of the body to 105 which the top is attached. The top is, of course, supported in upright position by means of any suitable forwardly led straps or lines 7, suitably attached to the body in advance of the top.

Supported on the body at, and partly beneath the rear end of the top, and on each

side of the center are casings 8, which are shown as cylindric and comprising a shell of any suitable material having a longitudinal slot in one side thereof, as shown in Fig. 6. The lower end of the casing, as shown, may be rounded or otherwise suitably shaped to fit in a suitable socket at the end of the top.

Threaded or otherwise secured on the upper end of the casing, is a cap 9, shaped to fit beneath the end of the top. An angular axle seat is provided in said cap to receive the angular end of a gudgeon 10, rotatably engaged on which is a spring impelled curtain roller 11, of a familiar or any suitable type. In the lower end of the casing is secured a foot-piece 12, having a cylindric seat therein to receive the cylindric gudgeon 13, secured on the lower end of the curtain rod or pole 11.

As shown, straps of metal 14, are provided on each side of said casing near the lower end thereof and provided with apertures therethrough, which are reduced or narrowed at their upper edges to engage over the heads of suitable bolts or attaching means secured in the back of the body and whereby the curtain casing is bracingly supported in upright position. If desired, corresponding parallel straps 15, may be secured at the upper end of the casing at any convenient point to be engaged positively on the brace bow, 4, for the top, or, if used in connection with a canopy, upon any stationary or rigid part of the construction. As shown, a drop curtain 16, is provided at the rear end of the top to close the space at the end of the top between the curtain casings.

40 The curtains 17, secured on the curtain rollers in the respective casings, may be of any suitable material and secured in place in any suitable manner. Each is of a width to extend from the top of the body 1, upwardly above the lower margin of the top, as shown in Fig. 5, and a band or strip 18, of any suitable material is secured around the top, as shown in Fig. 5, to afford between the same and the lower edge of a top 50 a recess or groove to receive the upper edge of the curtain. The forward or outer end of each curtain is rigidly secured to a suitable rod 19, or to any suitable means to prevent the end of the curtain being retracted 55 into the casing when the curtain is wound up.

As shown, the rod 19, is tubular and slidably engaged therein on each side the center are rods, each provided with a thumb piece 60 23, on its inner end projecting through a slot in the tubular rod 19. A spring 24, bears against the adjacent end of said rods in said tube and acts to hold the rods extended with their oppositely directed ends 65 projected beyond the ends of the tubular

rod 19, and in position to engage in sockets in the rail of the body and also in recesses in the guide groove in the top of canopy. In the drawings, a lining strip 25, is shown in the space between the top cover 2, and the outer facing strip 18, and openings are shown through the lining strip corresponding in position with the sockets in the rail.

Studs or buttons 20, of any kind also, may be secured in the bows for the top, some of 75 which are arranged closely adjacent to the lower margin of the top, while others are arranged but a short distance above the top of the body.

The curtain for each side of the car may 80 be provided with corresponding apertures to receive the studs therein. The studs or buttons are arranged an equal distance apart on each of the bows and on the shield 3, thereby permitting the curtain to be adjusted to close the entire side of the car or to close merely the rear end of the bow 21, or to close the entire space to the front bow 22, as preferred. Of course, the upper edge of the body may be grooved, as shown in 90 Fig. 5, if desired, to assist in holding the lower edge of the curtain in place. This, however, is not essential. Of course, if preferred, the curtain may be drawn on the inner side of the bows where installed, as 95 shown in Fig. 1, or on the inner side of the supporting columns or stanchions for a canopy top. Where so arranged, the curtains may be readily adjusted from within the car or vehicle without necessitating 100 stopping and without interfering with the convenience of the operator or passengers.

While I have shown the device installed 105 in connection with a cape top, it is to be understood that the particular type of top is quite unimportant, or the arrangement of the bows or other supports therefor, and although I have shown a particular form of casing for the curtain, any suitable construction for the purpose may be used permitting the ready retraction of the curtains and the protection of the same from injury by the sun and the weather or otherwise 110 when not in use.

Of course, the location of the particular 115 curtain casings will depend upon the structure to which the same is to be applied. The construction permits of many different arrangements, one of which is illustrated in Figs. 9 and 10, in which the wind shield 120 25^a, is hingedly connected at the top of the dash at the rear of the hood. The side frame members of said shield are tubular metal curtain casings 26, the curtains 27, of which may be drawn rearwardly and attached to any suitable part of the body of the car or to the bows by means of buttons 28, or any other suitable attaching means. These curtains may be of any suitable size or shape and may, if desired, ex- 125 130

tend down to, or below the top of the body or front doors, and afford a wind guard for the operator (or those occupying the front seats) from all lateral winds.

5 Of course, details of construction and application may vary, and I do not purpose limiting the patent to be granted on this application otherwise than necessitated by the prior art.

10 I claim as my invention:—

The combination of a top on a vehicle and roller side curtains associated therewith, of a windshield, the end members thereof tu-

bular, and spring shield curtain rolls concealed therein and adapted to be extended 15 to meet the extended side curtains, said top, wind shield, and respective side curtains acting to inclose the space over the interior of the vehicle.

In testimony whereof I have hereunto 20 subscribed my name in the presence of two subscribing witnesses.

ALBERT E. COOK.
